UNITED STATES PATENT OFFICE.

JOSEPH R. WELLER, OF DE GRAFF, OHIO.

LABEL-HOLDER.

SPECIFICATION forming part of Letters Patent No. 605,213, dated June 7, 1898.

Application filed September 3, 1897. Serial No. 650,454. (No model.)

To all whom it may concern:

Be it known that I, JOSEPH R. WELLER, a citizen of the United States, residing at De Graff, in the county of Logan and State of Ohio, have invented certain new and useful Improvements in Label-Holders, of which the following is a specification, reference being had therein to the accompanying drawings.

My invention relates to an improved label-holder designed particularly for use in connection with druggists' bottles; and it has for its object the production of a label-holder of such construction as to adapt it for being easily and quickly secured to a bottle of any shape.

The invention will first be described in connection with the accompanying drawings and then pointed out in the claim.

Figure 1 of the drawings is a perspective view of a bottle with my improved label-holder in place, a number of labels being shown in the holder. Fig. 2 is an enlarged perspective view of the label-holder, partially broken out to show the means for preventing accidental displacement of the labels. Fig. 3 is an enlarged horizontal sectional view of the same.

Referring to the drawings, A represents my improved label-holder, comprising a broad base 1 of thin elastic material, such as celluloid or the like, and a box-like pocket 2, open at top and closed at bottom, centrally secured to the base, the pocket being made of the same material as the base and preferably of a single blank, the lower end 3 and side walls 35 4 being bent inward and glued or otherwise secured to the base, as clearly shown in the drawings. Immediately in rear of the pocket a tongue 5 is cut in the base, the base forming the rear wall of the pocket, and bent inward, extending some distance into the pocket, forming a spring adapted to press against the labels in the holder and prevent their accidental displacement when pouring from the bottle.

45 The label-holder is designed to be secured to a bottle B by gluing or cementing the base

1 to the body of the bottle, as shown in Fig. 1. By securing the holder to the bottle labels C contained in the holder and designating the contents of the particular bottle to which the holder may be attached are convenient to the druggist, and mistakes frequently arising from using the wrong label are easily avoided.

By constructing my label-holder with a broad thin elastic base I am enabled to adapt the holder for use in connection with bottles of any shape, as the base will accommodate itself to the shape of the bottle, as will be evident, thus permitting the holders to be manufactured in large quantities without regard to the particular shape of the bottle to which they may be applied. Furthermore, by constructing the base of elastic material I secure an easy and cheap manner of forming the spring-tongue for holding the labels in place.

I am fully aware that label-holders for use with bottles have been heretofore constructed; but all such holders with which I am familiar have rigid bases specially formed so as to conform to the shape of the bottle to which they are to be attached, and I am not aware that any label-holder has been made before that is equally applicable to any bottle, whether its shape be round, square, octagonal, or otherwise.

Having thus described my invention, what I claim as new, and desire to secure by Letters Patent, is—

As an article of manufacture, a label-holder comprising a base of thin elastic material, a pocket secured to the base and adapted to contain a number of labels, the base forming the rear wall of said pocket, and a tongue cut in the base and projecting into the pocket.

In testimony whereof I affix my signature in presence of two witnesses.

JOSEPH R. WELLER.
